UNITED STATES PATENT OFFICE.

ARTHUR H. DOWN, OF NEW HAVEN, CONNECTICUT.

FOUNTAIN-PEN.

SPECIFICATION forming part of Letters Patent No. 556,623, dated March 17, 1896.

Application filed October 11, 1895. Serial No. 565,350. (No model.)

To all whom it may concern:

Be it known that I, ARTHUR H. DOWN, a citizen of the United States, residing at New Haven, in the county of New Haven and State of Connecticut, have invented certain new and useful Improvements in Fountain-Pens; and I do hereby declare the following to be a full, clear, and exact description of the invention, such as will enable others skilled in the art to which it appertains to make and use the same.

My invention has for its object to provide a fountain-pen which shall operate by gravity instead of capillary feed, and which shall be so constructed that agitation is not necessary to cause the ink to feed, but which will feed at all times and without leakage, and in which bubbling of the ink will not take place under any circumstances.

With these ends in view I have devised the novel fountain-pen of which the following description, in connection with the accompanying drawings, is a specification, numbers being used to designate the several parts.

Figure 1 is a longitudinal section of my novel fountain-pen complete; Figs. 2 and 4, enlarged detail plan views of the head and finger; Fig. 3, a section on the line *xx* in Fig. 2, and Fig. 5 is a front end elevation as seen from the left in Fig. 4.

1 denotes the reservoir, and 2 the threaded plug by which the base of the reservoir is closed and which is provided with an opening 3. At the other end of the reservoir is a nozzle 4, also threaded to engage the reservoir.

7 denotes a pen-carrying rod, 6 a head at the outer end of the rod, and 8 a barrel within the reservoir, which is provided with spiral slots 9 and a rod 10, which passes through opening 3 in the block and is rigidly secured to a base-piece 13, so that rotation of the base-piece will carry the rod and the barrel.

19 denotes a cap which is threaded to engage the base-piece when the pen is in use, or to engage the nozzle to cover the pen proper when the latter is not in use. At the inner end of the pen-carrying rod is a pin 17, which passes through the spiral slots in the barrel and the ends of which engage longitudinal

grooves 18 in the inner side of the reservoir, so that rod 7, the head and the pen are normally held against rotation; but when the

base-piece and barrel are rotated pin 17 is caused through its engagement with the spiral slots in the barrel to travel longitudinally in 55 grooves 18 and to carry the pen outward into operative position or to retract it, as may be required.

28 denotes the pen, the edges of which are bent to form wings 29, which incline toward 60 each other and engage bevels 30 on the head, whereby the pen is made self-locking.

None of the parts herein described are of my invention, and I make no claim thereto broadly.

My invention consists in providing the head and pen-carrying rod with a longitudinal opening 32, which extends from end to end thereof, the outer end of the opening lying under the pen proper, as clearly shown in Fig. 1, and the inner end terminating near the lower end of the reservoir. As a matter of fact, as shown in the drawings the opening 32 is closed by pin 17. This may be obviated by making the hole through the pen-carrying 70 rod larger than the pin, so that air may pass freely into the barrel and thence to the reservoir around the pin, or by forming a hole 33 in the pen-carrying rod, which shall intersect with opening 32, as shown in Fig. 1; and my invention furthermore consists in providing the head with a forwardly-extending finger 34, which rests closely upon the top of the pen and is provided with a slot 35 extending through it. This slot may extend to the end 80 of the finger, dividing it into two parts, as in Fig. 2, or may be closed at the end, as in Fig. 4, as may be preferred. The inner end of this slot terminates in a groove 36 in the head, said groove extending to the inner end of the 85 head. This construction enables me to produce a fountain-pen operating by gravity instead of by capillary attraction, which will feed readily at all times without shaking, which will not leak, and in which bubbling 90 of the ink is wholly prevented. This result is accomplished by means of the longitudinal opening in the pen-carrying rod, which admits air to the base of the reservoir to take the place of ink that is fed to the pen by 95 gravity.

When the pen is held in operative position ink will of course pass freely into groove 36 and will pass from the groove into the slot

when the latter is opened by pressure of the pen upon the paper in use. The sides of the slot lie close to each other, and the finger lies in contact with the pen, so that until the slot 5 is opened slightly by movements of the pen in use no ink can pass down to the pen.

The operation is very satisfactory owing to the fact that the ink-supply is controlled automatically by the pressure which the user 10 exerts upon the pen.

Having thus described my invention, I claim—

1. In a fountain-pen a pen-carrying rod having a head by which the pen proper is carried, a groove in said head extending to the inner end thereof, and a finger extending forward from the head which lies above and in contact with the pen and is provided with a slot communicating with the groove, the 15 said slot being normally closed when the pen is not in use said head and pen-carrying rod

having a longitudinal opening extending from end to end whereby air is admitted to the reservoir to take the place of ink which in use passes from the groove into the slot when 25 the latter is opened by movement of the pen.

2. In a fountain-pen the combination with a pen-carrying rod and a head having a longitudinal opening through them, said head having a groove 36, of a finger extending forward from the head which lies above and in contact with the pen and is provided with a slot 30 extending into the groove the said slot being normally closed when the pen is not in use substantially as described for the purpose set 35 forth.

In testimony whereof I affix my signature in presence of two witnesses.

ARTHUR H. DOWN.
